ARTHUR W. BERRESFORD, OF MILWAUKEE, WISCONSIN, ASSIGNOR TO THE CUTLER-HAMMER MFG. CO., OF MILWAUKEE, WISCONSIN, A CORPORATION OF WISCONSIN.

CASING FOR RESISTANCES.

1,080,947.

Specification of Letters Patent.

Patented Dec. 9, 1913.

Application filed July 10, 1909. Serial No. 506,934.

To all whom it may concern:

Be it known that I, ARTHUR W. BERRESFORD, a citizen of the United States, residing at Milwaukee, in the county of Milwaukee and State of Wisconsin, have invented new and useful Improvements in Casings for Resistances, of which the following is a full, clear, concise, and exact description, reference being had to the accompanying drawing, forming a part of this specification.

My invention relates to improvements in inclosing casings for resistances.

Where resistances are inclosed for the purpose of protection it is customary to provide apertures in the inclosing casing to permit a free circulation of air between the resistance units to prevent the same from overheating. Such apertures are usually provided in the top and bottom of the casing as this arrangement insures the best ventilation. Even though inclosed resistances are well ventilated, they are, nevertheless, apt to become overheated and burn out. This causes the formation of arcs tending to pass upwardly through the apertures in the top of the casing. Furthermore, upon burning out of the resistances molten resistance material and solder flow through the apertures in the bottom of the casing. Consequently, with ordinary inclosing casings there is great danger of starting fires upon the burning out of the resistances.

My invention, therefore, has for its object to provide a casing which will insure proper ventilation of the resistances and also prevent the escapement of any flames or molten material therefrom upon the burning out of the resistances.

For the purpose of more fully disclosing the nature of my invention, I shall describe the embodiment thereof illustrated in the accompanying drawing. It should be understood, however, that my invention is not limited to the particular structure shown in the drawing, but is capable of various modifications.

In the drawing, Figure 1 is a perspective view of a device having my invention applied thereto; Figs. 2 and 3 are perspective views of parts of the device. Fig. 4 is a longitudinal sectional view taken through a portion of the device; and Fig. 5 is a per-

spective view of the preferred form of one of the parts of Fig. 4.

For the purpose of illustration, I have shown my invention applied to a starting rheostat of a conventional type. The rheostat comprises resistance contacts 1, a controlling element 2 and a retaining magnet 3, all of which are mounted in the usual manner upon an insulating panel 4. The panel 4 is secured by means of bolts 5 to the resistance inclosing casing, the structure of which I shall now describe.

In practice, the casing may assume various different forms. The particular casing illustrated is in the form of a rectangular box, being provided with a back 8, side pieces 9, a top 10 and a bottom 11. The box may be formed of any preferred size and of any preferred material. Furthermore, the box may be constructed in various different ways. As illustrated, the back and sides of the box are formed integrally, while the top and bottom thereof are formed of separate pieces. For supporting the casing, I have shown lugs 12 having angular portions to which the sides and top and bottom of the box are secured by suitable means, such as rivets 13 or screws 14. In practice, the resistance units may be mounted either in the casing or on the back of the insulating panel 4. However, it is customary to mount the units in the casing. This may be done in various different ways. One method of mounting the resistance units in the casing is shown in Fig. 2. As illustrated in this figure, the resistance units 15 are mounted vertically in the casing and spaced a suitable distance apart. To insure proper ventilation of the units 15, I have provided apertures 18 in the top and bottom of the casing. This permits a free circulation of air through the casing, to prevent overheating of the units 15.

To prevent escapement of molten metal through the apertures in the bottom of the casing, I preferably provide a receptacle 19 adapted to be secured to the underside of the bottom portion 11 in any preferred manner. As illustrated, the receptacle 19 merely comprises an oblong pan of the same width and depth as the casing and having inclined side portions. For securing the re-

ceptacle 19 to the casing I have shown screws 20 adapted to fit into screw threaded apertures 21 in the bottom portion 11. In order to prevent the receptacle 19 from obstructing the circulation of air through the ventilating apertures, I preferably provide spacing washers 22 surrounding the screws 20 which maintain the receptacle 19 at a suitable distance from the underside of the casing.

For preventing the escapement of flames from the casing, upon burning out of the resistance units, I have provided a hood, the structure of which I shall now describe. 15 This hood comprises an outer portion 23 and an inner portion 26. The hood is preferably of substantially the same width and depth as the top 10 of the casing and is adapted to rest directly thereon. The opposite ends of the inner and outer members are closed, while the other ends thereof are open, thereby providing a tortuous flue for the escapement of air and gases passing through the apertures in the top of the casing. In 20 practice, the hood may be formed in any preferred manner and secured to the casing by any preferred means. As illustrated, the hood is adapted to be secured to the casing by means of a screw 27 adapted to fit into a screw threaded aperture 28 in the top 10 of the casing. The hood is preferably arranged to snugly fit between the supporting lugs at opposite sides of the casing so as to prevent the same turning. The portion 26 of the 25 hood in reality forms a baffle plate for deflecting any flames produced upon the burning out of the resistances. The path provided for such flames, as indicated by arrows, insures the extinguishment thereof before they can leave the hood. While it may appear that the hood obstructs the circulation of air for ventilation, it has been found in practice that it does not do so to any appreciable extent. Consequently, the casing 30 thus produced not only provides for proper ventilation, but obviates all danger arising from the production of flames and molten metal upon the burning out of the resistances.

50 In Fig. 5, I have illustrated the preferred manner of forming the member 26 of the hood. This construction provides upwardly extending side pieces 30 which form means for maintaining the members 26 and 23 in a spaced relation without the use of any special fastening means.

Having thus described my invention what I claim as new and desire to secure by Letters Patent is:—

60 1. An inclosing casing for resistances having a reflex ventilating flue.

2. A rheostat comprising a resistance element, an inclosing casing therefor, said casing having ventilating openings in its top

and bottom and solid vertical walls and top 65 and bottom guard pieces for said casing, said top guard piece serving to confine flames emerging from said casing and said bottom guard piece serving as a receptacle for descending substances. 70

3. An inclosing casing for resistances having a tortuous ventilating flue at the top thereof, ventilating apertures at the bottom thereof and a hollow receptacle disposed beneath the ventilating apertures. 75

4. An inclosing casing for resistances having ventilating apertures in the top thereof and a hood arranged on the top thereof, said hood having a tortuous flue therein.

5. An inclosing casing for resistances comprising a box portion having ventilating apertures in the top and bottom thereof, a hood arranged on the top of said box portion and having a baffle plate arranged therein and a hollow receptacle disposed below 85 the apertures in the bottom of said box portion.

6. A hood for resistance inclosing casings having a reflex opening therein.

7. A hood for resistance inclosing casings 90 comprising an elongated member substantially U-shape in cross section and closed at one end and a baffle plate arranged within said member to form a tortuous flue.

8. A hood for resistance inclosing casings 95 comprising two elongated portions substantially U-shape in cross section, and arranged one within the other, said portions having opposite ends thereof closed and being spaced from one another to form a tortuous 100 flue.

9. In a rheostat, the combination with a box body having open ends, of a pair of plates closing said ends and held by the box body, resistance coils supported between said 105 plates, said plates having ventilating apertures therein, and guard-pieces covering the ends of the box body at a distance from said plates leaving a space between the said ends of the box body and the plates, said space 110 communicating with the atmosphere, whereby a circulation of air is permitted.

10. In a rheostat, the combination with a box body having top and bottom plates provided with ventilating apertures therein, resistance coils supported by and between said plates and removable guard pieces covering the apertures in said plates, said guard pieces and said plates being spaced to permit circulation of air through the ventilating 120 apertures in said plates.

11. In a rheostat, in combination, an insulating panel for the resistance controlling contacts, a resistance casing secured to said insulating panel, said casing having top and bottom plates provided with ventilating apertures therein, said casing and said panel together forming an entirely closed recepta-

8

cle except for the ventilating apertures in the top and bottom plates, resistance units supported between said plates, and top and bottom guard members covering the ventilating apertures in said plates but spaced from said plates to permit circulation of air through the ventilating apertures therein.

In witness whereof, I have hereunto subscribed my name in the presence of two witnesses.

ARTHUR W. BERRESFORD.
